CLAIM

The ornamental design for a testing device holder for endoscope, as shown and described.

DESCRIPTION

FIG. 1 is a top, front and right side perspective view of a testing device holder for endoscope showing our new design;

FIG. 2 is a bottom, rear and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a perspective view of the testing device holder for endoscope in a position of use with a testing device and endoscope; and,

FIG. 9 is a perspective view of the testing device holder for endoscope in a position of use with a testing device and tube. The broken lines in the drawings illustrate portions of the testing device holder for endoscope and form no part of the claimed design.

The broken lines showing the portions in FIGS. 8 and 9 are for illustrative purposes only and form no part of the claimed design.

1 Claim, 9 Drawing Sheets
